UNITED STATES PATENT OFFICE.

ANTHONY VON DER WULBEKE, OF NEW YORK, N. Y.

TABLE.

SPECIFICATION forming part of Letters Patent No. 279,290, dated June 12, 1883.

Application filed August 24, 1882. (No model.)

To all whom it may concern:

Be it known that I, ANTHONY VON DER WULBEKE, of the city of New York, county and State of New York, have invented a new and useful Improvement in Tables, of which the following specification is a full, clear, and exact description.

This invention relates to an improved table, which, when not in use, may be swung upward and held in place against a wall, to serve as a picture, mirror, or other ornament.

The invention consists in the combination of a wall with a hinged platform, a plate projecting beyond the edge of the platform, and with a leg pivoted to the plate and adapted to be swung upon the platform, all as hereinafter more fully set out.

The invention also consists in the details of construction hereinafter more fully pointed out.

In the accompanying drawings, Figure 1 is a perspective view of a portion of a room provided with my improved table, showing it swung up to serve as an ornament. Fig. 3 is a perspective view of a portion of a room, showing my improved table let down for use. Fig. 2 is a view of the device on a larger scale than the other figures.

Similar letters of reference indicate corresponding parts in all the figures.

The letter A represents one of the walls of a room. B is the floor.

To the wall A is hinged, at proper height, the platform a of a table. This platform is at its free end provided with a plate, b, which projects beyond the edge of the platform, and to which is pivoted a leg, c. This leg is equal in length to the distance the platform a is hinged from the floor. When the platform is let down, as in Fig. 3, to serve as a table, the leg c supports its free end, the upper edge of said leg being concealed beneath the plate b, as shown; but when the table is to be converted into a room ornament the leg c is revolved to rest

upon the top of platform a, and then said platform is swung upward against the wall, to which it is held by a spring-catch, d, or in equivalent manner. In this position the leg c is concealed between the wall A and platform a, as shown in Fig. 2. A lever, e, and spring f serve to release the catch d when it should be desired to again lower the platform.

g is a ledge fastened to the wall A a short distance beneath the hinged edge of the table, to serve as an additional support.

The lower side of the platform a—to wit, the side exposed when the platform is swung up—is provided with a suitable ornament, such as a mirror or picture.

My invention may also be applied to benches, as shown in the drawings, which may be hinged to the wall at the right and left of the table, if desired. a' a' represent two such benches. b' b' are the projecting end plates; c' c', the pivoted legs, and d' d' the catches, all operating in the same manner as hereinabove described with relation to the table.

It will be seen that by my invention the furniture of a room may be rapidly removed, and at the same time the room ornamented by swinging said furniture up against the wall. In this way a dining-room or public resort may be converted into a dancing-hall of attractive appearance in a very short time. The invention is also useful when the floor of a room is to be temporarily cleared for cleaning purposes.

I claim as my invention—

The combination of wall A with hinged platform a, plate b, projecting beyond the edge of platform a, and with leg c, pivoted to plate b and adapted to be swung upon platform a, substantially as specified.

ANTHONY VON DER WULBEKE.
